UNITED STATES PATENT OFFICE.

PAUL BUTLER, OF LOWELL, MASSACHUSETTS.

CARTRIDGE-SHELL-TRIMMING MACHINE.

SPECIFICATION forming part of Letters Patent No. 681,299, dated August 27, 1901.

Application filed October 28, 1895. Serial No. 567,156. (No model.)

To all whom it may concern:

Be it known that I, PAUL BUTLER, of Lowell, county of Middlesex, State of Massachusetts, have invented an Improvement in Cartridge-Shell-Finishing Machines, of which the following description, in connection with the accompanying drawings, is a specification, like letters on the drawings representing like parts.

The present invention relates to a machine for finishing the outer ends of cartridge-shells, either metallic or paper, the said ends usually being rough or uneven after the shells are otherwise complete. In the case of metallic shells the machine operates to trim the end and bevel the inner edge of the mouth of the shell, so that the open end of the shell will be perfectly smooth and circular and its inner surface slightly flaring for the ready entrance of the bullet. A similar operation is necessary in the case of paper shells, except that in this case a different tool is used, which is adapted to iron or smooth the outer edge of the shell and give it a true circular outline.

25 The machine embodying the present invention is adapted to receive shells fed thereto upon a movable carrier having an intermittent feed, whereby the said shells are consecutively carried to a predetermined position in which they are held stationary, while the finishing-tool is brought into a position to coöperate with the said shells to perform the desired finishing operation.

The present invention consists mainly in 35 a novel combination of instrumentalities whereby these ends may be accomplished, and is embodied in a machine comprising a carrier adapted to receive the shells, a rotating cutter or ironing-tool to operate upon a shell or a gang of such tools operating simultaneously upon two or more shells, a holder 40 for each shell, adapted to confine it in the proper position to be operated upon by the aforesaid tool, and an operating-shaft adapted 45 by its rotation to cause the said parts to operate in such relation to each other as to perform their functions in a proper manner.

Figure 1 is a top plan view of a machine embodying the present invention; Fig. 2, a 50 longitudinal vertical section through the axis of the main shaft thereof; Fig. 3, an end elevation looking toward the left of Fig. 1, with

parts of the cam-wheel broken away to show the carrier and feeding mechanism behind it, a portion of the carrier also being shown in 55 section; Fig. 4, a vertical cross-section on line x^4 , Fig. 2; Figs. 5 and 6, details of the shell-holder, being respectively a side and end elevation thereof; Fig. 7, a detail of the track or support for carriage b ; Figs. 8, 9, 60 and 10, details of the cutters for metallic shells, and Fig. 11 a modification showing an ironing-tool for finishing paper shells.

The machine embodying the present invention consists of one or more tool-shafts a , 65 mounted to rotate in a reciprocating carrier b , longitudinally movable in a track c at the base of the machine. The said carrier is actuated by a cam d upon the main shaft B and during the movement produced by a revolution of said main shaft carries the tools e^2 , 70 connected to the shafts a , to and from the shells to be operated upon, which are fed to a carrier f , provided with intermediate feed mechanism coöperating with the reciprocating carriage, so that the shells are brought to a position to be operated upon by the tools e^2 at the forward movement of the carriage b 75 and at the next feed movement of the carrier, which takes place as the carriage b recedes, 80 are carried forward beyond the path of the tools toward a suitable clearer or ejector by which the finished shells are removed from the machine. The same feed movement of the carrier brings other unfinished shells into 85

the position to be operated upon at the next forward movement of the carriage b . The said tool-shafts a , which may be of any desired number, (the machine as herein shown having three of such shafts,) are mounted in 90 bearings b^2 upon the said carriage b , and, as herein shown, said carriage is sleeved upon the main shaft B of the machine, which extends longitudinally from one end to the other thereof and is driven by a belt upon the pulley B^2 . To produce the reciprocating movement above described, the said carriage is provided with an arm b^3 , extending outward therefrom longitudinally with relation to the machine and provided with a cam projection 100 b^4 , extending into the cam-groove d , formed in a hub d^2 upon the main shaft B and secured thereto, so as to rotate therewith, preferably by means of screws d^3 , extending through the

webbing of the pulley B^2 into the end of the said hub d^2 . Thus as the shaft rotates the cam-groove will engage the cam projection b^4 , causing the entire carriage b to travel back and forth, carrying with it the tool-shafts a , which are mounted to rotate therein. As herein shown, the cam projection b^4 is longitudinally adjustable with relation to the carriage, so that the position thereof at its forward movement may be varied when it is desired to operate upon shells of different lengths. To this end the said cam projection is secured to the arm b^3 by means of a bolt b^5 , bearing in upward projections b^6 and prevented from longitudinal movement with relation thereto by a hub b^7 , so that as the said bolt is turned the cam projection b^4 will be longitudinally moved with relation to the said arm, thus determining the limit of movement of the carriage b . The said cam projection when thus adjusted may be locked in position by means of a nut b^8 , as shown.

The tool-shafts a above described are adapted to receive at their outer ends suitable tools e^2 to operate upon the ends of the cartridges, and the said tools are detachably secured thereto by means of a tongue e^3 , inserted in a socket a^2 at the end of shaft a and secured therein by a set-screw a^3 . The shafts thus carrying the tools are provided with pulleys a^4 , adapted to be constantly rotated by a belt a^5 , passing alternately around said pulleys, as best shown in Fig. 4.

In order that the cutter-shafts a may be prevented from longitudinal movement with relation to their bearings b^2 during the operation of the machine and at the same time be to some extent adjustable longitudinally, the said bearings b^2 are in extensions at the upper part of the carriage b , between which extensions the pulleys a^4 are adapted to fit closely. The said pulleys a^4 in turn are mounted upon the shafts a and secured thereto by set-screws a^6 , so that by loosening the set-screws the shafts a may be moved with relation to the said pulleys. Thus by loosening the said set-screws and moving the shafts longitudinally with relation to the pulleys and bearings the position arrived at by the tool during the forward movement of the carriage may be modified.

In order that such adjustment may be delicately effected, an extension b^9 is provided at the back of the carriage, the said extension being of sufficient width to cover the rear ends of all the tool-shafts, and through the said extension are screwed bolts b^{10} , one for each of said shafts, adapted to engage therewith, so that by turning the said bolts the said shaft may be moved forward with relation to the bearings b^2 and pulleys a^4 . Thus if it is found that the cutting-tools are not moved forward by the carriage to a sufficiently-advanced position to properly trim the shells the set-screws a^6 upon the pulleys may be loosened and the bolts b^{10} screwed in so that the ends thereof engage the ends of the

shafts a , forcing the said shafts forward to the desired position, after which they may be secured by tightening the set-screws a^3 , while the bolts b^{10} are locked in position by the lock-nuts b^{11} . Thus at each complete revolution of the main shaft of the machine the constantly-rotating cutter or trimming-tools are advanced by the carriage b , operated by the cam-groove d , to a certain position and afterward withdrawn therefrom, and in order that said tools may be caused to operate as desired upon the cartridge-shells it becomes necessary to provide mechanism for bringing the said shells consecutively to a position in which they will be operated upon by said tools during the forward movement thereof and holding them stationary in such position until the operation is performed. For this purpose a carrier for the shells is provided consisting of the wheel or disk f , having a bearing, as shown, upon the main shaft B , but not connected to rotate therewith, and having upon its periphery a series of transverse recesses f^2 , each adapted to hold a cartridge-shell, the said shells preferably being fed thereto through a chute g , leading downward from the receptacle g^2 , adapted to contain the unfinished shells. The shells are so fed to the said chute that as they pass down the carrier they will fall into the transverse recesses of said carrier with their open ends projecting inward toward the center of the machine, the finishing-tools being arranged on an arc corresponding to the circumference of the carrier and projecting toward the periphery thereof and so spaced that each one is directly opposite one of the recesses f^2 upon said carrier, and thus adapted when it approaches the same during the forward movement of the carriage b to coöperate with the mouth of the shell held therein and perform the necessary operation thereon. Thus, assuming that the carrier f is stationary, with shells in the recesses f^2 opposite the cutting-tools e^2 , a rotation of the main shaft B will through the action of the cam-groove d cause the carriage b to approach the said carrier f , so that the rotating cutting-tools e^2 enter the open ends of the shells upon the carrier, trimming and finishing the same, as is desired, the carriage afterward being withdrawn by the latter half of a single revolution of the shaft.

In order that the tools at the next revolution of the shaft may again perform their functions upon a new set of unfinished shells, it is necessary to provide feed mechanism for the carrier and arrange said feed mechanism to operate during the movement of the tools from and to their operative position. This is preferably accomplished, as shown herein, by means of a ratchet f^3 , Fig. 3, connected with the carrier and adapted to coöperate with the pawl h , pivoted at h^2 upon an arm i , made fast to a rock-shaft i^2 , extending longitudinally through the machine, from the opposite end of which rock-shaft projects an

arm i^3 , Fig. 4, coöperating by means of a projection i^4 , Figs. 1 and 2, with a cam j on the inner periphery of the pulley B^2 . As the pulley B^2 rotates, therefore, in the direction 5 of the arrow, Fig. 4, the projection i^4 rides upon the cam j , rocking the shaft i^2 and actuating the pawl h , the cam being so positioned with relation to the cam-groove d that it reaches the projection i^4 when the said cam- 10 groove d is operating to withdraw the carriage b from the carrier f so that when the said carriage is thus withdrawn the rock-shaft i^2 actuates the pawl h , moving the carrier f forward, the teeth of the ratchet f^3 being so 15 spaced that the completed shells are carried beyond the line of the finishing-tools, while other incomplete shells in the carrier are brought into a position to be operated upon at the next forward movement of the said 20 tools. In order to restore the pawl h at the end of each feed movement, so that it will engage another tooth of the ratchet-wheel ready for the next feed movement, the arm i^3 is arranged so that its weight tends to rock the 25 rock-shaft i^2 toward the right, Fig. 4; but in order to make the operation thereof more positive a guard j^2 is provided within the pulley B^2 , adapted to coöperate with the cam j and engage the projection i^4 from the arm i^3 30 when it reaches the end of the cam j ; so as to insure the movement of the rock-shaft in the right direction. The pawl h is held in engagement with the ratchet-wheel f^3 by means of a spring h^3 , connected to the arm i , as by 35 screws h^4 , and bearing upon the upper surface of the said pawl.

In order that the feed movement of the carrier may be slow and gradual, thus obviating the danger of overthrowing or passing beyond 40 the point at which the carrier should stop, as might be likely to occur owing to the momentum of the carrier if the feed movement were sudden or rapid, the cam j is made, as shown, with a gradual upward slope extending 45 some distance around the periphery of the pulley B^2 , so that the movement of the rock-shaft which actuates the pawl is gradual, causing the carrier to move slowly, so that it acquires very little momentum. As an additional safeguard, however, it is best to provide a retarding device, and such a device is herein shown, consisting of a split collar f^4 , fitted closely around a hub or projection f^5 from the carrier f , the said collar being 55 supported upon an upright f^6 , secured to the bed-plate of the machine.

In providing for the proper feeding of the shells it is obvious that the carrier must be arranged to move forward a number of spaces 60 equal to the number of tools employed in order to prevent the same shell from being operated upon twice, while the tools must be so spaced that a shell finished by a tool will be carried to a point which is not opposite the next one. As shown herein, the bearings of the tool-shafts occupy so much space that it 65 is impracticable to place the tools as near to-

gether as are the recesses on the carrier, and they are accordingly arranged four spaces apart, so that the second feed movement carries the shell previously finished by the first cutter two spaces beyond the second cutter, while the third feed movement carries it one space beyond the third cutter, the two unfinished shells immediately behind it being finished by the third and second cutter, respectively, at successive operations. In other words, the first cutter operates on every third shell beginning with the first, the second on every third shell beginning with the third, 75 and third on every third shell beginning with the second. The result is attainable by placing two cutters any number of spaces apart not equal to their own number or a multiple thereof. 80

It is obviously necessary for the carrier to stand at exactly the right position when the tools are acting on the shells, since otherwise the tools might not register properly with the shells, in which case the shells would be 85 spoiled, while the machine itself might be damaged. In order to secure the proper positioning of the carrier at the end of each feed movement, a centering and locking projection b^{12} is secured, as by bolts or cap-screws b^{13} , to the front of the carriage b , the said projection being adapted to move with the carriage toward the periphery of the carrier f , the end thereof passing into one of the recesses f^2 , and thus locking the carrier in 90 proper position. As clearly shown in Fig. 2, the main portion of said projection b^{12} is substantially the same in shape as the recesses f^2 and will thus fit closely therein, preventing any movement of the carrier f , while the 95 end of the said projection b^{12} is made somewhat tapering, so that it will enter the recess even if the carrier is slightly out of its proper position, and by its further movement will act as a wedge to bring the carrier to the 100 right position and lock it there during the operation of the tools.

In order that the shells may be firmly held in the carrier during the time when the tools are operating thereon and at the same time be readily fed thereto and detached therefrom, temporary holders k are provided, one corresponding to each of the tools and arranged to coöperate with the shell in the recess opposite said tool. In order that the said holders may not interfere with the feeding of the shells, they are arranged to operate intermittently to correspond with the intermittent feed movement of the carrier—that is to say, they are arranged to engage the shells after the carrier has stopped with the shells in position to be operated upon by the tools and to be disengaged therefrom at the end of such operation in order to permit the onward feed movement of the carrier. To attain this end, the said holders consist of arms pivoted in lugs k^2 upon the top of an upright A , in which is formed one of the bearings for the shaft B , and the said arms extend outward over the 115 120 125 130 135

carrier, each being provided with a clamp portion k^3 , adapted when the said arm is rocked on its pivot to close down upon the upper side of the shell, thus holding it firmly 5 in its recess upon the carrier. The said clamps are preferably pivotally supported at k^4 , (see Fig. 5,) so that as they are pressed down upon the upper surface of the shell they will move upon their pivots into substantial parallelism therewith, and they are each provided with a spring k^5 , adapted to hold them substantially in the position shown in Fig. 5, and are, as shown, mounted in a slot k^6 at the end of the arm k , whereby they 10 are longitudinally adjustable with relation to the said arm to a greater or less extent, as may be desired. The said arms k are normally held in the position shown in Fig. 2 by means of springs k^7 , the said position being such that the shells are not engaged by the clamps, but are free to move under the said clamps during the feed movement of the carrier. In order to cause the said clamps to operate at the end of each feed movement, 15 and thus hold stationary the shells at that moment in position to be operated upon, each of the said arms is provided with a cam-roll k^8 beyond the pivotal support k^2 , and the said cam-rolls when the arms k are in their normal position rest upon the surface m^2 of a cam-wheel m , mounted upon the main shaft B, so as to rotate therewith. The said cam-wheel is provided with cam-surfaces m^3 , consecutively arranged, as shown, each of 20 said cam-surfaces extending over only a portion of the periphery of the cam-wheel m and being arranged one in advance of the other, while the cam-rolls k^8 are so positioned with relation to the surface of the cam-wheel m that each one is adapted to co-operate with one of said cams and not with the others. Thus, referring to Fig. 1, it will be seen that as the shaft B rotates in the direction of the arrow shown upon the cam-wheel m in the foremost of the said cam-surfaces m^3 will pass the first two of the cam-rolls k^8 without engaging therewith, while the second of said surfaces m^3 will pass the first of said cam-rolls, the third cam-surface, however, being positioned to reach the first of the cam-rolls at the time when the other two cam-surfaces respectively meet the other two cam-rolls, thus practically lifting all of the said cam-rolls simultaneously and rocking all of the clamping-arms k upon their pivots, so as to clamp three shells in their respective carrier-recesses at the same time. The cam-surfaces m^3 are of such length as to maintain the holders k in their clamping position during the 40 operation of the cutters upon the cartridge-shells held thereby, but terminating consecutively when the shaft B has reached that portion of its revolution at which the carriage b has been withdrawn by the cam-groove d to disengage the tools from the shells previously held. The cam-rolls k^8 then descend from the cam-surfaces m^3 , and the holders k are

restored to their normal position (shown in Fig. 2) by means of the springs k^7 , above mentioned. Thus during a single rotation of the main shaft B the carrier f is fed forward a predetermined distance, the holders k are brought into engagement with the shell to be operated upon, the tools are advanced toward the said shells by the movement of the carrier, so as to perform their operations on the said shells, and are again withdrawn from the carrier, the holders released, and the carrier again fed forward, carrying the finished shells beyond the point at which the cutting-tools operate and bringing a new set of unfinished shells to the operating position, after which the operation is repeated. The limit of movement of the holders k can be adjusted for shells of different sizes by changing the position of the cam-roll, the bearing k^9 for which is vertically adjustable in the slot k^{10} by means of the screw k^{11} and nut k^{12} . 85

The clamps above described, while being operated with sufficient pressure to prevent the shell from being lifted out of the groove, are not necessarily capable of holding the shell firmly in its proper longitudinal position against the thrust of the cutting-tool engaging therewith. For this reason an abutment A², projecting from the upper part of the upright A, is provided, the said abutment following the periphery of the carrier, so as to be opposite to the tools, the face of the abutment being close to the rear of the carrier, so that as the carrier rotates the rear ends of the shells will bear against the said abutment, the shells thus being held longitudinally while the cutters are operating thereon. 95

In order to remove the finished shells from the carrier as the said carrier is fed onward, a clearer f⁷ is provided, consisting of a thin strip or plate of metal extending into a slot f⁸ upon the periphery of the carrier f, the said plate having a curved edge f⁹ beginning 100 within the said slot and curving outward therefrom beyond the periphery of the carrier, so that as the shells approach the said plate they are engaged by the edge f⁹ and carried outward from the carrier thereby, as will be 110 clearly seen by reference to Fig. 3, where a portion of the carrier-wheel is shown in section with the plate f⁷ in elevation. 115

In order to clear the recesses f² of any dust or metal chips which may have collected 120 therein and which might, if allowed to remain, alter the position of the shell with relation to the tools and thus cause damage, a brush or clearer may be employed, such a device being shown herein as consisting of an ordinary 125 brush n, (see Fig. 3,) mounted on an arm n², supported in an undercut slide or guideway n³, just below the chute g, through which the shells are fed to the carrier. The said arm n² is adapted to travel in said guideway, and thus carry the brush n across the periphery of the carrier and longitudinally through the recesses f² therein, and, as shown herein, the said arm n² is connected by a link n⁴, Fig. 1, 130.

to an arm n^5 , pivoted at n^6 to a portion of the frame of the machine. The said arm n^5 is adapted to be engaged by a projection n^7 , extending outward from the carriage b , the said 5 projection being shown in dotted lines, Fig. 3, so that as the carriage moves forward it rocks the arm n^5 upon its pivot n^6 , moving the brush across the periphery of the carrier, and the said brush is then moved back to its 10 normal position by means of a spring n^8 when the carriage b moves back, so that the projection n^7 no longer pushes the arm n^5 . As has been above mentioned, the carriage b , as clearly shown in Fig. 2, is sleeved or mounted 15 upon the main shaft B of the machine, so as to be longitudinally movable with relation thereto, but is mainly supported in the track or guideway c , mounted upon the bed of the machine, and the said track or guideway is 20 preferably contained in a supplemental supporting portion c^2 , having transverse slots c^3 , (shown in detail Fig. 7,) said slots having an inclined surface adapted to be engaged by a wedge-shaped key c^4 . The track or guideway 25 c is supported on the upper surface of the key or keys c^4 , two being shown herein, so that the carriage b is capable of a slight vertical adjustment, or, in other words, may be trued up until it is exactly centered upon the main 30 shaft B , so that the said shaft is relieved of the weight of the carriage and frictional resistance to the longitudinal movement of the carriage, as well as to the rotation of the shaft, which would be caused by the said weight 35 upon the shaft. As herein shown and as thus far described, the machine is adapted to trim and finish metallic shells, and the cutters may be of any construction suitable for that purpose, one of said cutters, however, being 40 shown in detail in Figs. 8, 9, and 10 and having a guide projection or tongue e^4 at its outer end adapted to enter the mouth of the shell, the said tongue being tapering and provided with a cutting-blade e^5 , contained in a slot e^6 45 and secured by a screw e^7 , thus being longitudinally adjustable, said cutter being adapted to bevel the inner edge of the end of the shell, while a second knife or blade e^8 extends radially from the said tongue, so as to trim 50 the extreme end of the shell during the rotation of the tool. The blade e^8 , as herein shown, consists of a single piece having cutting edges on opposite sides and a squared portion between adapted to be held in a transverse opening e^9 through the projection e^4 by a set-screw e^{10} entering the end of said projection. The 55 machine, however, is equally well adapted for finishing paper shells, it being necessary only to substitute an ironing-tool for the cutting- 60 tools above described and to slightly modify the carrier to fit the paper shells. A practical tool for this purpose is shown in section in Fig. 11, said tool consisting mainly of a tapering tongue or mandrel e^{20} , adapted to enter 65 and engage the inner surface of the shell and provided with a collar e^{20} , secured thereto in any suitable way, as by a set-screw e^{21} , the

outer end of the bore of said collar preferably being slightly countersunk, as shown, so as to taper from its outer edge inward toward the point at which the body of the collar joins the mandrel e^{20} . Thus a recess is formed, into which extends the end of the shell, the outside of which is smoothed by the sides of the opening in the collar, while the inner surface 75 is smoothed by the tapering mandrel. The said mandrel is preferably provided, as shown, with grooves e^{21} , extending from its point or outer end back to a point beyond the collar e^{20} , thus forming channels through which bits 80 of material removed from the inner surface of the shell by the said mandrel are free to work back and drop out. The nature of the tools, however, is obviously not essential to the invention, since a tool of any kind can be 85 employed, the substitution of one for another requiring but slight modification, if any, in the general construction of the machine.

I claim—

1. In a cartridge-shell-finishing machine, 90 the combination with the driving-shaft, of a rotatable carrier for the shells, means for automatically feeding shells to said carrier, a reciprocating tool-carriage movable in a direction parallel to said shaft toward and from 95 said carrier, a tool or gang of tools mounted on said carriage and adapted to be advanced thereby to a position to operate on the shells in said carrier, and connecting mechanism between said shaft and said shell-carrier and 100 tool-carriage respectively for producing an intermittent feed movement of said carrier and reciprocating movement of said carriage, substantially as described.

2. In a cartridge-shell-finishing machine, 105 the combination with a reciprocating tool-carriage, of a rotating shell-carrier, comprising a wheel or disk mounted on a horizontal axis and having transverse recesses along its periphery, a feed-chute for the shells inclined 110 toward the periphery of said carrier, mechanism for intermittently rotating said carrier during the reciprocation of said carriage and holding devices adapted to hold the shells while said carrier is stationary and release 115 them prior to the next movement thereof, substantially as described.

3. In a cartridge-shell-finishing machine, 120 the combination with a driving-shaft, of a tool or tools having a reciprocating movement parallel to said shaft; a carrier for the shells 125 consisting of a disk coaxial with said shaft and having recesses on its periphery and so positioned with relation to the tools that shells carried in said recesses are in a position to be operated upon by said tools at one extremity of their reciprocating movement; an intermittent feed mechanism for said carrier; devices for holding shells in the recesses of 130 the carrier when said carrier is stationary and releasing said shells before the next feed movement of the carrier, and one or more cams carried by said shaft to operate said devices, substantially as described.

4. In a cartridge-shell-finishing machine, the combination with a reciprocating finishing-tool; of a carrier adapted to bring the shells successively to a proper position to be operated upon by said tool; an intermittent feed mechanism for said carrier coöperating with said reciprocating tool; and a centering and locking device connected with said tool and adapted to engage said carrier during the forward movement of said tool, substantially as described.
5. In a cartridge-shell-finishing machine, having reciprocating tools, the combination with a carrier for the shells consisting of a rotating disk having recesses on the periphery thereof, and intermittent feed mechanism; of a brush movable transversely across the periphery of said carrier; and means for moving said brush when said carrier is stationary between successive feed movements thereof, as and for the purpose described.
6. In a cartridge-shell-finishing machine having a carrier for the shells and reciprocating tools adapted to approach and recede from said carrier during the operation of the machine, the means for reciprocating said tools consisting of a cam projection connected therewith and coöperating with a cam-groove on the shaft of the machine, and a device for adjusting the position of said cam projection to vary the limit of movement of said tools, as and for the purpose described.
7. In a cartridge-shell-finishing machine, the combination with the main driving-shaft, of the carrier for the shells, loosely mounted on said shaft and free to rotate independently thereof, a reciprocating tool-carriage movable in a direction parallel to said shaft and adapted to move a finishing-tool to and from the shells supported in the said carrier during the operation of the machine; a rotating tool mounted in a bearing on said tool-carriage; and means for longitudinally adjusting said tool in said bearing, substantially as described.
8. The combination with a carrier for cartridge-shells consisting of a rotary disk having recesses on the periphery thereof and provided with intermittent feed mechanism, of a holding device for the shells consisting of a pivotally-supported lever having a clamp at one end thereof normally held above the said carrier to permit the movement thereof, and a cam coöperating with the carrier feed mechanism adapted to engage the end of said lever opposite the said clamp and by rocking said lever to cause said clamp to engage a shell in said carrier, said cam being arranged to operate between successive feed movements of the carrier, substantially as described.
9. A cartridge-shell-finishing machine consisting of a reciprocating tool-carriage sleeved upon the main shaft of the machine; a cam-groove extending around said shaft and engaging a cam projection from said carriage to produce a reciprocating movement there-

of; a carrier for the shells consisting of a disk having recesses in its periphery, said carrier also having a bearing on said shaft; feed mechanism operated by said shaft to produce intermittent rotary movement of said carrier; and a locking or centering device for said carrier consisting of a projection from said carriage adapted during the forward movement thereof to enter a recess in said carrier, substantially as described.

10. The combination with the reciprocating tool-carriage, of a carrier for the shells consisting of a rotary disk mounted on a horizontal axis and having recesses in the periphery thereof, a ratchet connected with the said disk, a pawl adapted to engage said ratchet; a cam for actuating said pawl having a gradually-inclined surface; and a retarding device for said carrier, substantially as described.

11. In a machine for operating on cartridge-shells, the combination with the driving-shaft, of a rotatable carrier having a bearing on said shaft, a reciprocating tool-carriage sleeved upon said shaft and longitudinally movable with relation thereto, a cam carried by said shaft for producing a reciprocating movement of said tool-carriage toward and from said carrier, and connecting mechanism between said shaft and the carrier for producing an intermittent rotation of said carrier, substantially as described.

12. The combination with the horizontal driving-shaft mounted in supports at or near the ends of the supporting-frame, and the reciprocating tool-carriage movable in a direction parallel to said shaft, of the rotatable carrier for said shells mounted on said shaft and provided with intermittent feed mechanism, holding devices adapted to engage the shells in said carrier, said devices being mounted on one of the supports for said shaft, and a cam-wheel mounted on said shaft and adapted to engage and operate said holding devices, substantially as described.

13. In a machine for operating on cartridge-shells, the combination with the driving-shaft provided with a driving-pulley, of a rotatable carrier for the shells coaxial with said shaft, and a cam on said pulley adapted to coöperate with said carrier to produce rotation thereof, substantially as described.

14. The combination with a horizontal driving-shaft mounted in supports at or near the ends of the supporting-frame, of the rotatable carrier for said shells mounted on a horizontal axis, a tool-carriage movable in a direction parallel to said shaft, a track for said carriage on the supporting-frame of the machine, means for producing a reciprocating movement of said carriage along said track from the rotation of said driving-shaft, and feed mechanism also coöperating with said shaft to produce an intermittent rotary movement of said carrier, substantially as described.

15. In a machine for operating upon cartridge-shells, the combination with an inter-

mittingly-fed carrier for the shells, of a holding device adapted to coöperate with said carrier to hold the shells therein, said holding device comprising a pivoted arm extending over the carrier, a cam for moving said arm with relation to said carrier, and a cam-roll adjustably connected to said arm, substantially as described.

In testimony whereof I have signed my name to this specification in the presence of 10 two subscribing witnesses.

PAUL BUTLER.
